Sept 4, 1835 Nathaniel Richardson Boston.

Letters Patent

The Schedule referred to in these Letters Patent and making part of the same containing a description in the words of the said Nathaniel Richardson himself of his improvement in the Bedstead for the sick called Richardson's Alleviator.

Be it known that I Nathaniel Richardson of Boston County of Suffolk and State of Massachusetts have made an improvement in the Bedstead for the sick called Richardson's Alleviator which is described as follows. The posts and rails of this Bedstead A. & B are made similar to those in common use. In fig 1 of the annexed drawing C and D. represent moveable frames hinging on hinges which may be elevated or depressed to any angle required. E is a slot and key by which the two moveable frames may firmly united when it is required to raise the whole bed at the same time. F F pieces of wood framed into the two inside of the upper moveable frame with pulleys G. G. in them and hinging on cords hereafter described. H is a revolving rail. I. J. catch & wheel ~~are~~ fixed on the ends of the revolving rail. K. K. pulleys to secure the ratchet wheel L crank handle to turn the revolving rail. M. M. cords to raise the frame or frames one end of each cord being fastened to the side rail of the bedstead and the other wound around the revolving rail. Operation. The frames being fit down upon the rails of the Bedstead and it is required to raise the whole bed the key is inserted into the slot which secures the two frames together as one frame. the crank handle is turned which turns the revolving rail and winds the cords around it and thus raises the frame. The ratchet wheel and pulley secure the revolving rail from returning and the bed is thus kept at any angle required. When it is desired to raise the upper half of the bed alone. The key is removed from the slot and by the

9034

left described position the lower half of the frame would be
main stationary whilst the upper half would be elevated
What I claim as my invention and desire to have by lettering
Patent consists in the combination and arrangement of the parts
of the apparatus for elevating and depressing the beam as before described
but I claim no part of the Bedstead itself
